UNITED STATES PATENT OFFICE.

FLOYD O. ENFIELD, OF PLEASANT LAKE, INDIANA.

AUTO-JACK.

1,180,117.

Specification of Letters Patent. Patented Apr. 18, 1916.

Application filed April 13, 1915. Serial No. 21,108.

To all whom it may concern:

Be it known that I, FLOYD O. ENFIELD, a citizen of the United States, residing at Pleasant Lake, in the county of Steuben 5 and State of Indiana, have invented certain new and useful Improvements in Auto-Jacks; and I do hereby declare the following to be a full, clear, and exact description of the invention, such as will enable others 10 skilled in the art to which it appertains to make and use the same.

This invention relates to vehicle jacks, and one of the principal objects of the same is to provide a jack of simple construction 15 which will lift an axle and wheel of an automobile, and hold them in elevated position without the expense of much power.

Another object of the invention is to provide a jack to be operated by foot power, 20 and which will hold the axle elevated by the relative disposition of the pivotal points of the foot lever and the lifting member.

The foregoing and other objects may be attained by means of the construction illustrated in the accompanying drawing, in which—

Figure 1 is a side elevation showing the jack in use, and Fig. 2 is a perspective view of the jack showing the foot lever thrown 30 outward.

Referring to the drawing, the numeral 1 designates the support for the jack, said support being formed preferably of a metal bar bent into substantially U-shape, the 35 cross member 2 of the support forming the base to rest upon the ground or floor. Pivotally connected near the base to the support 1 are metal links 3, said links being pinned at 4 to the vertical portions of the support 1 on opposite sides. The links 3 are pivoted at 5 to a lifting member 6, comprising space vertical members connected together at their lower ends by the bar 7. The members 6 are provided with a series 40 of perforations 8, and pivotally suspended between the members 6 on the pin 9 is a yoke 10.

The upper ends of the member 6 are curved as at 11, and an operating lever is 50 pivoted at 12 to the curved portions 11. The operating lever comprises two bars placed side by side, and having divergent ends 13, which are pivoted at 14 to the upper ends of support 1. The operating lever

is provided at its outer end with a foot pedal 55 15, having side flanges 16.

The operation of the jack may be briefly described as follows: The axle *a* of the auto vehicle is inserted in the yoke 10, after the operating lever has been thrown upward 60 into the position shown in Fig. 1, and by placing the foot upon the pedal 15 the operating lever is depressed to lift the axle and wheel off the ground. The perforations 8 permit a vertical adjustment to accommodate 65 axles of different heights.

From the foregoing it will be obvious that a jack made in accordance with this invention will lift a heavy vehicle without great power being applied owing to the disposition 70 of the pivoted parts.

Various changes may be made in the details of construction without departing from the spirit and scope of the invention as defined in the claim.

What is claimed is:—

A lifting jack comprising a U-shaped support, the web of said support forming the base, links pivotally connected to the inner faces of the arms of the support adjacent the web, a lifting member comprising a connecting bar, vertical arms connected to the opposite ends of the connecting bar, said vertical arms provided with a plurality of spaced openings and their outer 85 ends curved, said links being pivotally secured to the outer face of the vertical bars adjacent the connecting bar, an operating lever comprising a shank having outwardly diverging members at one end pivotally secured in the upper ends of the arms of the U-shaped member their outer ends pivotally connected to the curved arms of the lifting members, the opposite end of the stem provided with laterally projecting members at 90 opposite sides thereof to facilitate the moving of said lever downwardly, a yoke adjustably mounted in the openings of the vertical bars of the lifting member to compensate for receiving the different size axles 95 100 therein, substantially as set forth.

In testimony whereof I affix my signature in presence of two witnesses.

FLOYD O. ENFIELD.
